UNITED STATES PATENT OFFICE

2,347,605

CLOSURE FOR BOTTLES, JARS, AND
SIMILAR CONTAINERS

Charles D. Magnesen, Chicago, Ill.

Application April 18, 1940, Serial No. 330,238

4 Claims. (Cl. 215—45)

My invention relates generally to a closure member or cap adapted to effectively close and seal the mouths or openings of bottles, jars, metal cans or other containers and which may be applied and removed by hand as many times as desired.

My invention relates more specifically to a device of the character described particularly adapted for use with bottles, jars or other containers which have a comparatively small neck and mouth and are not readily capped or uncapped with the closure members at present on the market.

While the general construction of my improved cap may be similar to that shown and described in United States Patent No. 2,045,480, issued June 23, 1936, to Hooker Magnesen and myself, yet my present invention is directed to a type of cap which is not at present on the market and contains a great many advantages over the construction of the above mentioned patent.

One of the principal objects of my invention is to provide an improved cap which attains a high and uniform degree of effectiveness in closing or sealing the mouths of bottles or other containers to which it is applied, notwithstanding some irregularities in the size or shape of the necks of bottles or other containers to which it is applied.

A further object of the present invention is to provide a simple and inexpensive cap which can be cheaply manufactured and which can be applied and removed easily by manual operation a large number of times without becoming bent or distorted or losing its effectiveness.

A further object of the present invention is to provide an improved cap for small-necked bottles or other containers provided with a foil seal which must be destroyed before the cap can be removed, thereby insuring the contents of the container are not adulterated or in any way tampered with after the original contents were sealed in.

A further object of the invention is to provide an improved cap for small-necked bottles or similar containers so constructed that the cap may be removed after the foil seal is torn off, by grasping the cap in one hand between the two first fingers and the thumb and by pressing down on a raised portion of the cap with the thumb and pulling up with the fingers on the edges of the cap.

A further object of the invention is to so construct the cap that the same may easily be replaced on a container by simply pressing down on the edges of the cap.

Other objects and advantages will be more apparent from the following description wherein reference is had to the accompanying two sheets of drawings, upon which

5 Fig. 1 is a front perspective view of a portion of a bottle neck showing my improved closure member in position and with the forefinger and thumb of a person's hand shown in dotted lines removing the foil seal on the cap;

10 Fig. 2 is a similar front perspective view of the cap and bottle neck after the seal has been removed and the outer cap member has been raised by placing the thumb on the cap button and the two first fingers beneath the edge of the outer member, in which position the cap is removed from the bottle;

15 Fig. 3 is an enlarged top plan view of the cap member;

20 Fig. 4 is an enlarged cross sectional view through the neck of a bottle with the cap in sealing position thereon taken on the line 4—4 of Fig. 3;

25 Fig. 5 is a view similar to Fig. 4 except with the foil seal removed and the outer member in raised position adjacent the top of the cap button so that the closure member can be removed;

Fig. 6 is a perspective view of the foil seal;

Fig. 7 is a perspective view of the top member;

30 Fig. 8 is a perspective view of the outer member, and

Fig. 9 is a perspective view of the gasket which is formed of rubber or other material.

In the preferred embodiment of my invention which I have chosen to illustrate, in Figs. 6 to 9 of the drawings I have shown the four parts which when assembled together provide the cap assembly and seal that form the subject matter of my invention. These parts may comprise the foil seal 10 shown in Fig. 6, the top member 12 shown in Fig. 7, the outer member 14 shown in Fig. 8, and the sealing washer 16 shown in Fig. 9. The outer member 14 which is formed of sheet metal may comprise a cylindrical cup having an annular rolled over edge 18 at its open end 20 and an axially disposed cylindrical opening 22 formed in its bottom wall 24.

The top member 12 which is formed of sheet metal, or other material having some resiliency, may also be in the form of a cup-shaped member having a cylindrical wall 26 which is cut out at regular intervals to form a plurality of finger members 28. Each of the finger members is provided intermediate its ends with an outwardly disposed corrugation 30, the corrugation being 55 aligned so that the same may be formed in one

operation before the spaces are cut out between the fingers. Similarly, the lower ends of the fingers are curled or formed with inward rolls 32 which are also aligned so that the same may be made in a single operation. The top member is provided with a flat horizontal upper wall 34 which has projecting upwardly therefrom a reduced circular portion 36 terminating in the closed wall 38 forming in effect a button upon the top member. The portion 36, which is cylindrical and disposed axially of the wall 26, has a slight outward bulge 37 just beneath the top wall 38 of the same, for a purpose which will be hereinafter described.

The outer member 14 and the top member 12 are assembled together as shown in Fig. 4, with the button portion extended upwardly through the axial opening 22. After these two parts are assembled together the outward bulge 37 is made in the button portion so that the same can not pass through the opening 22 in the outer member 14, but may be moved back and forth most of the distance between the wall 38 and the wall 34. The gasket or ring member 16 may be positioned within the top member 12 lying against the under side of the wall 34 so that when the assembly is placed upon the open end 42 of a bottle neck 44, the same may effect an annular seal around the top of the same.

In applying the cap or closure member thus assembled to a bottle or other container, the elements will be in the position shown in Fig. 5, with the fingers 28 yielding sufficiently to permit the rolls 32 to pass into the groove of the bottle neck below the upper bulge and make resilient or frictional engagement with the same. To securely lock the cap or closure member in position on the bottle top, the outer member 14 is then pushed downwardly over the inner or top member 12, the inner face of the cylindrical wall of the outer member bearing against and slightly pressing the fingers inwardly at their corrugations 30 and then bearing against the outside side of the rolls 32 as it comes opposite them, with the result that the inner member is frictionally stressed downwardly, and through the inherent elasticity of the rolls and their camming action against the upper face of the groove in the bottle neck, the fingers are drawn downward with a yielding pull in a manner similar to that described in the United States Patent heretofore mentioned herein.

In order to remove the closure member from a neck of a bottle or other container, the roll 18 of the outer member 14 may be grasped by the first two fingers, the thumb placed upon the top wall 38 of the cap and held there while the outer member is raised until it strikes the bulge portion 37 of the button as shown in Fig. 2.

From the above description it can readily be seen that I have provided a simple and effective closure member for small necked bottles, jars or other containers. By providing a button upon which the thumb may be placed and the edge of the outer member grasped with the two first fingers, a bottle cap of comparatively small size can be removed from or placed upon a container.

Bottle closures of the general type described are shown in the art, but so far as I am aware, none of them are so constructed as to exhibit effective longitudinal elastic stress upon the finger members, which in applicant's device is attained and contributed to in varying measure

by the cylindriform open end rolls of the narrow fingers, the transverse bends of such fingers, the bearing of the outer member of the closure upon the outer face of the transverse bends, and the flexible extended margin of the inner closure member extending beyond the seating face of the container top. Also, the fact that the outer member within which the top member is telescoped, is spaced from the top member so that the only frictional contact between the two parts occurs at the horizontal corrugations and the rolls on the fingers.

For the purpose of preventing undetected substitution of the contents of a container, I have provided a foil member 10, which may be of metal or any other suitable material. As shown in Fig. 4, the member 10 may be provided with a cylindrical portion 10a telescoped about the neck 36 of the button member with a slight outwardly extending flange 10b flattened out upon the wall 24 of the outer shell. I provide one or more annular grooves 10c in the wall 10a at a point directly below the bulge 37 on the button for the purpose of retaining the foil member in position on the same. The foil member may have an upper wall 10d applied over the top wall 38 of the button, with a disc-like segment 10e cut out of the same except for a small neck portion 10f which connects the disc portion to the foil member 10. When an original package of merchandise is purchased and the user wishes to open the bottle, he may grasp the disc member 10e between the thumb and forefinger as shown in dotted lines in Fig. 1, and tear the foil off the bottle generally on a path through the neck 10f. After the foil seal has once been removed it will of course be apparent to the observer that the closure member may be used indefinitely for sealing bottle tops. While I have illustrated in this embodiment a foil seal which is a separate unit from the closure member proper, it will be obvious that other means may be associated with the same for effecting a tamper-proof seal.

While I have illustrated and described a specific embodiment of the invention, it will be apparent to those skilled in the art that changes and modifications may be made in the various details shown, and I do not wish to be limited in any particular; rather what I desire to secure and protect by Letters Patent of the United States is:

1. A closure of the type described comprising a pair of telescopically slideable members connected together, one of said members being a top member having a raised button thereon, a ledge around the upper edge of the shank of said button, said member having an enlarged aligned cylindrical portion below said button and a plurality of relatively narrow longitudinally yielding fingers originating at and depending from the horizontal portion of said top member about the periphery thereof, each finger being formed with an outward horizontal corrugation intermediate its ends and with an inwardly curled resilient terminal portion, the outer telescopic member comprising a cylindrical shell of sufficient diameter to surround and contact the outward bulges of said fingers whereby the outer member is adapted to subject said fingers in a closing movement to pressure occasioning longitudinal extension of said fingers to thereby compensate for irregularities on the underside of the shoulder of a receptacle to which said fingers may be applied, said outer member having a flat upper surface

with an opening therein which surrounds the shank of the button on the top member permitting limited telescopic movement between the two parts, said ledge preventing separation of the same.

2. A closure of the type described comprising a pair of telescopically slideable members connected together, one of said members being a top member having a raised button thereon, a ledge around the upper edge of the shank of said button, said member having an enlarged cylindrical portion below said button and a plurality of relatively narrow longitudinally yielding fingers originating at and depending from the horizontal portion of said top member about the periphery thereof, said fingers adapted to grip under a shoulder of a receptacle to which the closure is applied, the outer telescopic member comprising a cylindrical shell of sufficient diameter to surround and contact said fingers whereby the outer member is adapted to subject said fingers in a closing movement to pressure to grip under the shoulder of a receptacle, said outer member having a flat upper surface with an opening therein which surrounds the shank of the button on the top member permitting limited telescopic movement between the two parts, said ledge preventing separation of the same and a foil seal member secured only to said button which must be mutilated before said closure can be removed.

3. A closure of the type described comprising a pair of telescopically slideable members connected together, one of said members being a top member having a raised cylindrical button thereon with the upper part of the same larger than the shank, said member having an enlarged aligned cylindrical portion below said button and a plurality of relatively narrow longitudinally yielding fingers originating at and depending from the horizontal portion of said top member about the periphery thereof, each finger

being formed with an outward horizontal corrugation intermediate its ends and with an inwardly curled resilient terminal portion, the outer telescopic member comprising a cylindrical shell of sufficient diameter to surround and contact the outward bulges of said fingers whereby the outer member is adapted to subject said fingers in a closing movement to pressure occasioning longitudinal extension of said fingers to thereby compensate for irregularities on the underside of the shoulder of a receptacle to which said fingers may be applied, said outer member having a flat upper surface with a circular opening therein through which the shank of the button on the top member extends permitting limited telescopic movement between the two parts but preventing separation of the same.

4. A closure of the type described comprising a pair of telescopically slideable members connected together, one of said member being an inner member having a raised button thereon, a ledge around the upper edge of the shank of said button, said member having an enlarged aligned cylindrical portion below said button, a ring gas ket disposed therein against the horizontal wall connecting the button and the enlarged cylindrical portion, said member having a plurality of longitudinally extending yielding fingers adapted when pressed inwardly to grip on the under side of the shoulder of a receptacle to which the fingers may be applied, the outer telescopic member comprising a cylindrical shell of sufficient diameter to surround and contact said fingers to force them under the shoulder of a receptacle said outer member having a flat upper surface with an axial opening therethrough which surrounds the shank of the button on the inner member to permit telescopic movement between the ledge and the horizontal wall of the cylindrical portion of said inner member.

CHARLES D. MAGNESEN.
